UNITED STATES PATENT OFFICE.

HORACE R. ALLEN, OF INDIANAPOLIS, INDIANA.

PULLEY.

SPECIFICATION forming part of Letters Patent No. 285,780, dated October 2, 1883.
Application filed May 5, 1883. (No model.)

To all whom it may concern:

Be it known that I, HORACE R. ALLEN, a citizen of the United States, residing at Indianapolis, in the county of Marion and State of Indiana, have invented a new and useful Pulley for Driving Machinery, of which the following is a specification.

My invention relates to improvements in pulleys in which I use a thin metallic disk 10 with corrugations running from the rim to the center, instead of spokes, to which I attach suitable cast-iron hubs and a rim in a manner hereinafter more fully described; and the object of my improvement is to make a lighter, stronger, 15 and cheaper pulley. I attain these objects by the mechanism illustrated in the accompanying drawings, in which—

Figure 1 is a side view of my pulley as it appears with the hub removed, the point of sight 20 being in the center of the axle; Fig. 2, a perspective view of the pulley with the hub removed, showing the radial corrugations and the attached rim; Fig. 3, a cross-section of the pulley on a line drawn through the center of the hub from opposite points of the rim; Fig. 25 4, a cross-section of pulley, in which, for additional strength, a double corrugated disk is used; Fig. 5, a perspective view of the cast-iron hub as removed from the balance of the pulley; Fig. 6, a plan showing the manner of 30 breaking joints in split pulleys, or pulleys made in halves; Fig. 7, a cross-section of a metal plate made specially for my pulley.

Similar letters refer to similar parts throughout the several views.

In the manufacture of my pulley I take a 35 rectangular sheet of metal, or, if more suitable, a sheet whose sides are curved, and by proper machinery bend the surface up into the corrugated forms A, Figs. 1 and 2. These corrugations are broad at one end, the broad end being formed always on the same edge of the sheet of metal, and are made to run tapering across the sheet to respective points in a line 40 that is parallel with the opposite edge of the sheet and at any required distance from it. This peculiar corrugated formation brings the two ends of the sheet together, forming a complete circular disk. This disk may be readily 45 formed from more than one piece, if desired. That part of the sheet between the apex of the

corrugations and the outer edge of the sheet is, at the same time the corrugations are made, bent at right angles to the face of the disk B, and forms the rim D. It will be seen that by 55 making the corrugations in the sheet this flange or rim will, in consequence of the corrugations, turn at right angles to the plane of the disk.

The rim is spun perfectly round and true, 60 and forms the support for a second rim of sheet metal, C, which is held in place by screws, or by the rivets d, and forms the face of the pulley. This flange gives the attached rim a firm support throughout the circumference of 65 the pulley. In many instances in pulleys for light work this outside and secondary rim may be dispensed with, and to obviate the tendency of the belt to slip over an iron pulley, I create more friction on the face by making the secondary or outside rim, C, of paper instead of 70 sheet metal. This outside paper rim is glued or otherwise solidly attached to the flange on the rim of the disk. I am also able to dispense with this secondary rim by using a metallic sheet rolled expressly for my purpose, and having the part to be bent up for the rim made heavier than the portion of which the disk is formed, as shown in cross-section in 75 Fig. 7, in which S is the part in which the corrugations are made, and s is the rim.

The hub may either be made in sections, as shown in the drawings, or it may be a single piece cast directly in its place on the metal disk. This is accomplished by adjusting the 80 corrugated disk in the molding-flask in its proper position, and then pouring in the melted metal for the hub, which cools and shrinks to the disk, making a very firm and solid pulley. The hub is then bored, the pulley placed 85 on a mandrel, and the flange or rim spun perfectly true and round. The hub shown in Figs. 3 and 5 is composed of three pieces. E is a collar having a bore to fit the shaft on which the pulley is to run. Notches to fit the radial corrugations in the disk are cast on the side of the collar next the disk. The central hole in the disk is larger than the bore of the collar E, 90 above referred to, and the intermediate space is filled by a metallic sleeve, F, which is a part 95 and continuation of the collar E. This sleeve F has a hole of the same bore as the collar E, 100

and has a screw-thread, *f*, formed on the outside of its outer end, for the purposes herein-after mentioned. *H* is a collar with a bore large enough to admit the sleeve *F*. It has 5 notches corresponding with the radial corrugations in the disk *B*, cast on the side next to the disk. *G* is a nut tapped to fit the thread on the collar *F*.

In practical operation the collar *F* is passed 10 through the hole in the disk *B*, the notches in the ring fitting in and filling the spaces between the corrugations *A A*. The ring *H* is then placed upon the collar from the opposite side, the notches filling the corrugations in the 15 disk and the disk being between the two collars. The nut *G* is then screwed on the end of the sleeve, bringing the two collars together and clamping the disk solidly between them.

When a very wide pulley is required, or for 20 any reason a single disk is not deemed sufficient, I combine the disks, as shown in Fig. 4, in which the collar *E* may have two projecting sleeves *F F*—one on each side—and a double set of notches—one on each side. Two 25 corrugated disks may then be adjusted, one on each side of the collar *E*, and are held in place by the two collars *H* and *H* and nuts *G* and *G*, shaped and combined as already described.

30 In Fig. 4, when very great strength is required, the two disks are reversed—that is, the faces now together are turned toward the outside, and the faces now turned outward are placed together, thus bringing the outer or 35 tapered ends of the corrugations near the outside edge of the face of the pulley.

In fastening my pulley to the shaft I use the ordinary key, or the set-screw of common form and application; but when my hub, composed of 40 the sections *E F G H*, is used I am able to clamp the pulley to the shaft by an arrangement in which the collar and sleeve *E F* are provided with a longitudinal slot, and the threaded end of the sleeve, *f*, is made tapering, so that when 45 the corrugated disk is placed between the two collars and the nut *G* is screwed up on the tapering end of the slotted sleeve *F*, the taper will bring the sides of the slotted sleeve together, thus decreasing the diameter of the hole 50 in the hub, and consequently clamping the pulley to the shaft.

When the pulley is to be split to enable it to be placed on a shaft without removing the shaft, all of the parts are made in halves, as 55 shown by the line *m m*, Fig. 1, and *z z* and *y y*, Fig. 5, and when put together are so adjusted that the parts will break joints, as shown in *m m*, *y y*, and *z z*, Figs. 5 and 6.

Having thus fully described my invention,

what I claim as new, and wish to secure by Letters Patent, is—

1. In a pulley, a disk of sheet metal connecting the hub of the pulley with the rim, the disk being composed of one or several sheets of metal, and having straight or spiral corrugations running from the rim to the center, substantially as described.

2. A metallic disk with corrugations running from the rim to the center, having a flange on its outer circumference at right angles to the disk and formed from the same plate as the disk, in combination with a stationary or an adjustable hub, substantially as described and set forth, and for the purposes specified.

3. An adjustable hub composed of the serrated collar *E*, with the sleeve *F*, the serrated collar *H*, and the nut *G*, in combination with the corrugated disk *B*, as described, and for the purposes mentioned and set forth.

4. A secondary and external rim, *C*, made 80 of paper, in combination with the corrugated disk *B* and its hub, substantially as described, and for the purposes specified.

5. A secondary and external rim, *C*, made of metal, in combination with the corrugated 85 disk *B* and its hub, substantially as described, and for the purposes specified.

6. A pulley having a corrugated disk, instead of spokes, made from sheet metal, extra thick on one edge, Fig. 7, the thick edge being turned 90 up for the rim, as described, and for the purposes specified.

7. In a split pulley, my method of combining the parts so they will break joints, or so no two lines of juncture, *m m y y z z*, Fig. 6, 95 will lie in the same vertical plane, substantially as described, and for the purposes specified.

8. An adjustable hub, in which the collar *E* and sleeve *F* have a longitudinal slot, and the sleeve *F* a threaded and slightly tapering end, 100 *f*, in combination with the collar *H*, the nut *G*, and the corrugated disk *B*, combined and arranged as described, and for the purposes specified.

9. The combination of the disk *B* with the 105 corrugations *A* and flange *D*, made from sheet metal of uniform gage, or from a sheet of varying gage, Fig. 7, the external rim, *C*, of metal or paper, a solid hub, as described, or a hub in sections *E F G H*, with or without the clamping device, making either a solid or a split pulley, arranged and combined, substantially as described, to operate in the manner and for the purposes set forth and specified.
